UNITED STATES PATENT OFFICE.

ORRIN GARDNER, OF EAST GROVELAND, AND JOHN L. MARTIN, OF CLARENCE, NEW YORK.

TONGUE-SUPPORT.

SPECIFICATION forming part of Letters Patent No. 666,614, dated January 22, 1901.

Application filed May 27, 1899. Renewed December 29, 1900. Serial No. 41,520. (No model.)

To all whom it may concern:

Be it known that we, ORRIN GARDNER, residing at East Groveland, in the county of Livingston, and JOHN L. MARTIN, residing at 5 Clarence, in the county of Erie, State of New York, citizens of the United States, have invented a new and useful Tongue-Carrier, of which the following is a specification.

Our invention relates to improvements in 10 tongue-carriers for machines used on farms.

Heretofore in tongue-carriers having a vertical shaft supported by a wheel the shaft or rod was mounted either in a casting bolted to the side of the tongue or in plates bolted 15 to the top and under side of the same. The tongue was thus unavoidably weakened to the extent of the holes bored, and it was therefore liable to be broken, particularly from the twisting strain caused by turning 20 corners. Farmers therefore distrust such a carrier and often decline to purchase it or to give it a trial. We have found such tongue-carriers wanting in suitable means or in any means at all for adjustment to the variable 25 positions of the tongue dependent upon the differing sizes of teams and the variable vertical adjustments of the machine both in the field and on the road. Again, the tongues of certain machines are coupled so low that 30 when cutting short grain no spring of suitable length can be used to take up the shocks caused by traversing the rough surfaces in fields. Furthermore, the draft-bar, if any is used, operates at unsuitable angles with the 35 vertical shaft when the tongue is elevated above a mean height and the lack of adjustment herein tends to prevent the free vertical play of the shaft in its bearings. As a consequence the use of the tongue-carrier is not 40 practical on the road or when the machine is trucked.

The primary objects of a tongue-carrier are to relieve horses of weight, to steady the tongue laterally, to steady the motion of the 45 gearing of the machine, and thus conserve the same, and to enable the driver of a harvesting-machine to operate the tilting-lever with ease. These objects have been partially attained in previous devices.

50 The objects of our invention, in addition to the above named, are to provide a tongue-car-

rier of such construction, first, that the full strength of the tongue may be preserved; second, that without change of length or set of spring it may be adjustably attached or 55 clamped to the tongue to suit the varying elevations or depressions of the same; third, that ample purchase on the vertical shaft may be secured, so as to reduce the twisting strain on the tongue when turning corners; fourth, 60 that there shall be a plurality of adjustments for the pivotal end of the draft rod or bar to offset any shift in the elevation or depression of the tongue; fifth, that one spring of suitable length may be used for all positions of 65 the tongue; sixth, that time and labor may be saved and less skill may be required in attaching the improved device, and, seventh, that it may be serviceably attached to a machine when on the road or when it is on trucks, 70 as well as in the field.

We attain our objects by the construction illustrated in the accompanying drawings, in which—

Figure 1 is a side elevation of the improved 75 tongue-carrier clamped to the tongue; Fig. 2, a vertical section of the same; Fig. 3, a rear elevation of the same when the bolster and twin shafts are used; Fig. 4, a view of the clamp and hook-bolts; Fig. 5, a view of 80 the substitute frame; Fig. 6, a view of the draft-rod.

Similar letters refer to like parts in the several views.

The frame or casting B is formed of two vertical side bars *b b*, placed edgewise to the tongue for strength and connected by two cross-bars V and U, the upper one having formed therein the eye S, Fig. 2, and the lower one the slot T. The vertical shaft or rod E 85 is mounted in the said cross-bars through the said eye and slot and is limited in downward movement by the detachable collar F, fastened at the upper end by the set-screw G. In place of the collar we reserve the option to 90 use a nut and to thread the shaft or to perforate the shaft horizontally and to insert a spring-cotter or a pin. The lower end of the shaft is beveled and inserted through a perforation in the crown J of the wheel-frame K 95 and riveted. Between the curved forks of the wheel-frame is journaled the wheel L upon 100

the axle-pin M. The wheel is led or guided by the draft-bar I, which, having formed there-in the eye S' at one end, is loosely sleeved, together with the spiral spring H, over the shaft 5 E upon the crown of the wheel-frame. The other end of the draft-bar is hinged or pivoted upon the pivot-pin R in the holder or guide P. The holder or casting is bolted to the tongue forward of the frame. It consists of 10 a plate having two curved pendent wings or ears Q, connected by a web N. The said ears have a plurality of horizontal perforations or pivot-bearings O, arranged (preferably, but not necessarily, in a curve) in graduated vertical order for the purpose of effecting suitable adjustments to offset any shift in the elevation or depression of the tongue. It is not essential that the wings or ears are curved. We reserve the right to make them of any desired form or size that will cover the range of vertical adjustment required.

Two clamps C C, provided with hook-bolts D D, inserted through a slot t, Fig. 4, in both ends of each clamp and secured by nuts, bind 25 the tongue to the frame B, the hooks being clasped over the edges of the frame. The ends of the clamps project beyond the upper and lower faces of the tongue and the bolts are adjusted against the same. By these 30 means it will be seen that no holes are bored in the tongue and that the full strength of the tongue is preserved; also, that a firm grip is secured on all sides of the tongue. The slots t t in the clamps provide for adjustability to 35 tongues unlike in thickness.

The slotted cross-bar U of the frame carrying the tongue rests upon the spiral spring H around the shaft. This spring both prevents the draft-bar from sliding up the shaft and 40 takes up all the jars of the machine. Any desired length of spring may be chosen for any kind of machine, and, if needful, the position of the cross-bar may be changed on the frame may be lengthened; but the improved 45 device enables us to use a frame and a spring of certain lengths and cover any required range of adjustment for any self-binder. By loosening the clamps the tongue may be raised or lowered and be reclamped at any desired point 50 of vertical adjustment.

The shaft rises and falls in its bearings owing to alternate spring compression and expansion, and this movement must be free. If we did not use the draft-bar, the shaft would 55 bind or lock. If we had no slot T in the cross-bar U, it would, nevertheless, do the same, because as the draft-bar and the tongue approach to and recede from each other the vertical shaft oscillates in a small arc longitudinally with the tongue.

Any shift of the tongue from a low to a medium or a high position changes the angle of the draft-bar with the shaft to one more acute, which causes the shaft to oscillate farther to and fro from a vertical position, thus requiring a longer slot in the cross-bar U and tending to bind or lock. Therefore in order

to offset any shift of the tongue in elevation or depression we have constructed the holder or guide P, having the choice of several vertical adjustments. The lowermost pivot-bearings in the same enable us to use the tongue-carrier when the machine is loaded on trucks for transportation. Other tongue-carriers fail herein for want of adaptation.

When turning corners, the draft-bar does not draw. The tongue pulls the carrier laterally, and as the latter is a rotating caster it tends to roll backward, impelled by the weight thereon. The effect on the tongue is a twisting strain. If the bearings in which the shaft is mounted are close together—about the thickness of the tongue, as in previous devices—the tongue has only a short purchase on the shaft to maintain it vertical when the wheel rotates to a right angle with the tongue. Hence a twist on the tongue is marked. In our arrangement the points of bearing are located in the upper and lower cross-bars of the frame and afford a long purchase on the shaft.

If we were to form the eye S in the lower cross-bar of the frame and the slot T in the upper cross-bar, the fulcrum on which the shaft acts would be shifted without detriment. We claim the option to make the change.

We do not confine ourselves to the form of the frame shown in Fig. 1. In Fig. 5 is shown a substitute or equivalent frame or casting. In this the vertical side bars b b are doubled at both ends for the purpose of producing narrow vertical slots W W, through which may be inserted ordinary headed bolts, which when furnished with washers would answer the purpose of hook-bolts. In adjusting the tongue up or down the bolts would slide along in both slots. In this frame the cross-bar U, containing the slot T, is placed above, but at some distance below the top, and the cross-bar V, containing the eye S, below. The double side bars b b are bent opposite the cross-bar U to suit the slot T, in which the shaft vibrates to and fro.

It is not essential that we use two clamps and four bolts. We can dispense with one double side bar b and the included slot by making the other stronger and using but one heavier clamp and two heavier bolts. We may employ this substitute frame inverted.

We do not limit ourselves to the construction described, in which the wheel is led at the side of the tongue. It is desirable to balance the weight of the tongue centrally over the wheel, particularly when the tongue is wide and the weight thereon unusually heavy. In Fig. 3 is shown the arrangement for guiding the wheel under the tongue. The main vertical shaft E is cut short, threaded at the end, and inserted through the hub y of the bolster X and confined by a nut Z. The bolster is provided with a slot at both ends, by which adjustment can be made to tongues unlike in width and through which the twin vertical shafts e e are inserted. The lower end of each shaft is threaded to receive the

5 nuts Z', which secure it to the bolster. No clamps are used, as two frames, preferably of the form shown in Fig. 5, are required to mount the twin shafts, and the tongue A is held between them by the bolts d. The upper 10 ends of the twin shafts are threaded to receive the nuts f f, or a collar similar to the collar F may be used to limit the downward movement. The cross-bar V, Fig. 5, rests upon the spiral spring h around each shaft.

We do not confine ourselves to the draft-bar I for guiding the wheel. In Fig. 6 is shown a draft-rod made of a single rod bent double to produce two parallel arms and having these 15 arms spread at the bend made in doubling to form the eye S' and having the ends of each arm bent to form the pivot-eyes S².

Having thus described our invention, we claim as new—

20 1. In a tongue-carrier, the combination, of an upright frame or casting adapted to have a tongue clamped or bound at any desired height thereto, seated on a spring, supported by a caster-wheel, and having loosely mounted therein a vertical shaft for a connection with said wheel, with the tongue having thereon a holder or casting to which is adjustably coupled or pivoted a draw-bar leading the said caster-wheel, and clamped or bound to said frame in such manner that the tongue may be shifted vertically and may be supported at any altitude within the limits of the vertical extension of the frame, substantially as set forth.

35 2. In a tongue-carrier, the combination, of an upright frame or casting adapted to have a tongue clamped at any desired height thereto, seated on a spring, supported by a caster-wheel, and having loosely mounted therein the vertical shaft of said wheel, with the tongue clamped or bound to said frame in such manner that the tongue may be shifted vertically and may be supported at any altitude within the limits of the vertical extension of the frame, substantially as set forth.

40 3. In a tongue-carrier, an upright frame or casting consisting of vertical or approximately vertical side bars connected by two cross-bars containing respectively an eye and a slot in which the vertical shaft of a caster-wheel may be mounted, and adapted to have a tongue clamped or bound thereto in such manner that the tongue may be shifted vertically and may be supported at any altitude within the limits of the vertical extension of the frame, substantially as set forth.

45 4. In a tongue-carrier, the combination, of

the upright frame or casting B, adapted to have the tongue clamped at any desired height thereto, and having loosely mounted therein 60 the vertical shaft E, having a wheel fork or frame bearing a wheel attached thereto and provided with a collar and with a spiral spring on which to seat the frame, with the tongue having thereon the holder P, containing a 65 plurality of vertically-arranged perforations, to which is pivoted at one end the draw-bar I, leading at the other end the said wheel by the said shaft inserted through the eye S', in the bar, and clamped or bound to the said 70 frame by means of the clamps C C, in combination with suitable bolts whereby the tongue may be shifted vertically and may be supported at any altitude within the limits of the vertical extension of the frame, substantially 75 as described and for the purposes set forth.

5. In a tongue-carrier, the upright frame or casting B, consisting of two vertical side bars connected by two cross-bars having respectively an eye and a slot in the upper and the 80 lower bar in which the vertical shaft of a caster-wheel may be loosely mounted, and adapted to have the tongue clamped or bound thereto by means of the clamps C C, in combination with the bolts D D, at any desired 85 height within the limits of the vertical extension of the frame, substantially as described.

6. In a tongue-carrier, secured to the tongue, the holder P, consisting of a plate having two parallel pendent wings or ears connected by 90 a web, the said ears having a series of horizontal perforations or pivot-bearings arranged in graduated vertical order for the purpose of pivoting thereto, at suitable angles and at such points as will offset elevations 95 and depressions in the adjustment of the tongue, the draft rod or bar leading a caster-wheel, substantially as described.

7. In a tongue-carrier, the combination, with the shaft E, having a wheel-frame bearing a wheel attached thereto, of the bolster X, having a hub at the middle in which said shaft is loosely mounted and having mounted in a perforation or slot at each end a vertical shaft provided with a spiral spring for suitable connections with the upright frames embracing the tongue, substantially as described and for the purpose set forth.
